Primary Examiner — Darlington Ly*Assistant Examiner* — Nasim Abdulaziz Ali(57) **CLAIM**

The ornamental design for a motor scooter, as shown and described.

DESCRIPTION

FIG. 1 is a front elevation view of a motor scooter, embodying my new design;

FIG. 2 is front and right side perspective view thereof;

FIG. 3 is a right side elevation view thereof;

FIG. 4 is a rear and right side perspective view thereof;

FIG. 5 is a rear elevation view thereof;

FIG. 6 is a rear and left side perspective view thereof;

FIG. 7 is a left side elevation view thereof;

FIG. 8 is a front and left side perspective view thereof;

FIG. 9 is a top plan view thereof; and,

FIG. 10 is a top and left side perspective view thereof, where features shown in broken line in the drawings are for illustrative purposes only and form no part of the claimed design.

1 Claim, 10 Drawing Sheets(56)
